UNITED STATES PATENT OFFICE.

EARLE W. CUMMINGS, OF OAKLAND, CALIFORNIA, ASSIGNOR TO GEORGE H. YOUNG, OF SAN FRANCISCO, CALIFORNIA.

SAW-TABLE SAFETY ATTACHMENT.

No. 801,889.

Specification of Letters Patent.

Patented Oct. 20, 1908.

Application filed November 16, 1907. Serial No. 402,405.

To all whom it may concern:

Be it known that I, EARLE W. CUMMINGS, citizen of the United States, residing at Oakland, in the county of Alameda and State of California, have invented new and useful Improvements in Saw-Table Safety Attachments, of which the following is a specification.

My invention relates to a safety attachment for sawing tables.

It consists in the combination of parts, and in details of construction which will be more fully explained by reference to the accompanying drawings, in which—

15 Figure 1 is a section on line $x-x$ of Fig. 3. Fig. 2 is an end view of my saw-table safety attachment. Fig. 3 is a side elevation of same.

It is the object of my invention to provide a means for protecting operators on saw and like tables from injury by reason of the lumber which is being sawed so catching in the saw as to be violently thrown backward, and either killing or severely injuring the operator by reason of the flying pieces or pieces of lumber.

I have here shown a sufficient portion of an apparatus to illustrate my invention.

Upon the sawing-table A is fixed a vertical standard 2 which is bolted or otherwise firmly secured near one side of the table and out of the direct line of the saw. An arm 3 is supported from this standard and projects out to one side therefrom in the plane of rotation of the saws, and line of travel of the lumber. This arm carries the safety-guards 4 and 5 which will be hereafter described. Various means may be employed for securing the arm 3 in place.

40 I have here shown the standard 2 as being made hollow and having a turnable head. Through this head passes a bolt 6 having nuts at top and bottom by which the whole may be securely locked in place. By loosening one of these nuts the head and the arm may be swiveled about so as to remove the safety-guards from their normal position and swing them out of the way so that work can be placed upon and removed from the 50 table, and easy access had thereto.

I have shown the standard as having lugs 7 upon it, and between these lugs is a turnable latch 8 which is so pivoted as to swing between the lugs and prevent the head and 55 connected parts from being turned; but when

it is desired to turn them this latch is swung up out of the way.

The safety-guard 4 may consist of a plate of wood or metal of sufficient strength, and it extends upwardly from the arm 3 having a sufficient height and width to protect the head and upper portion of the operator's body from anything which may fly backward from the saw. In the present case it is shown as supported by stout arms 4^a to 65 which it is bolted or riveted.

The guard 5 which protects that portion of the operator's body from the table up to the arm 3, consists of a series of fingers which are carried upon the arm 3, or a shaft extending through it. These arms have the lower ends pointed, and as they are allowed to swing freely upon their horizontal support, these points will engage the lumber which is being advanced on the table to the saw, so that if by any accident the piece of lumber should be so engaged that it would otherwise be violently thrown backward in the direction of the operator, or the rear of the table, these points will immediately engage and prevent it from being thrown backward; the angle of the arms 5 being toward the front, and the points acting as stops to prevent the lumber from being thrown backwardly. By reason of the independent bars 5, the points will easily conform to any irregularities of the surface of the piece to be sawed or worked upon by any other or equivalent tool. If it is desired to raise these guard strips so as to remove the lumber from the table, or for other purposes, it is effected by means of a spring-pressed handle 9 having upon one side a latch 10, which may be engaged with a catch 11 upon the upturned guard or its supports. 95

The handle may be pushed down so that its point or projection 12 on the opposite side from the latch, will engage a projection 11 on the contiguous arm 5. Each of these arms from one side to the other has a projection as at 13 adapted to interlock with a similar engaging part of the next arm so that when this handle is pushed down, and its pawl or arm engages the first of the arms 5, the continued downward pressure will raise all of these arms until the latch 9 engages with the stationary catch 11 of the upturned guard 4^a, thus holding the downwardly projecting guard arms in an elevated position, and allowing access to the 110

table or the work. In order to allow these arms to be moved, I have shown an elongated key or feather-way 14 made in conjunction with the central opening 15 which fits the shaft or support upon which the arms are turnable, and a feather 16 upon this shaft enters this key-way. The length of the key-way is sufficient to allow the raising of the arms to clear the table as previously described; and if it is desired to move the whole device temporarily, it is effected by swinging the arm 3 which carries the guards upon the vertical supporting standard 2.

Having thus described my invention, what I claim and desire to secure by Letters Patent is—

1. In an apparatus of the character described, a bar adapted to be projected over a sawing table, substantially parallel with the saw arbor, fingers independently turnable upon a shaft carried by the bar having points at the ends adapted to rest upon and engage the passing strip of lumber, lugs upon the sides of the fingers adapted to engage successively, a pawl carrying handle movable upon the same axis, and having a lug adapted to engage the first of the fingers when the handle is depressed, and latches with which the pawl may engage to retain the fingers in an elevated position.

2. In an apparatus of the character described, a support extending transversely above the sawing-table, substantially parallel with the saw arbor, a shaft carried by said support, pointed fingers adapted to engage the surface of the lumber, passing to the saw, and to prevent its return, a fixed shield projecting upward from the finger support, means for raising the fingers, said means including inter-engaging lugs, with a pawl and ratchet mechanism whereby the depression of the lever causes the engagement of the lugs, and a simultaneous raising of all the fingers.

3. In an apparatus of the character described, a vertical standard having a turnable head, an arm projecting horizontally

from said head into the plane of motion of the tool, means by which said head and arm are turnably engaged with the standard, a fixed guard extending upwardly from the arm, independently movable fingers extending downwardly having points to engage the passing material, and means by which said fingers are raised or released, said means including lugs adapted to engage the hubs of the fingers, a pawl-carrying handle turnable upon the finger support having a lug adapted to engage the first of said fingers, and catches with which the pawl may engage so that the turning of the handle will elevate all of the fingers out of contact with the surface beneath.

4. In an apparatus of the character described, a horizontally movable arm having a fixed guard extending upwardly therefrom in line with the tool, independent fingers turnably supported from the arm having points to engage the material, said fingers having engaging lugs upon the sides, a handle having a lug to engage one of said fingers and transmit motion to the others whereby the whole series may be raised to free them from the material below.

5. In an apparatus of the character described, a horizontally supported arm having a fixed guard extending upwardly therefrom, independent fingers turnably mounted upon the arm so that the points of said fingers may drop and engage the material passing beneath, the heads of the fingers having curved key-ways, a feather upon the shaft extending into the key-ways, a handle turnable upon the shaft having a lug to engage and raise the fingers, and a latch by which the handle and fingers are maintained in elevated position.

In testimony whereof I have hereunto set my hand in presence of two subscribing witnesses.

EARLE W. CUMMINGS.
